J. Bous.

Hot-Air Furnace.

Patented Mar. 29, 1834.

March 20, 1834
John Davis, Baltimore, Maryland
Setters Patent

The Schedule referred to in the Setters Patent and making part of the same copy
contains a description in the words of the said John Davis himself of his
improvement being a hot air furnace or apparatus for warming rooms with
warmed or heated air and expelling the cold air which in turn is also
heated....

Be it known that I John Davis of the City & County of Baltimore
and State of Maryland have made an improvement in the apparatus
being a hot air furnace or apparatus for warming rooms with warmed or
heated air and expelling the cold air which in turn is also heated denoted
as follows referring back to the annexed drawings

As regards the entire apparatus of which No. 1 is the receiver & 2 the furnace
or grate in which the anthracite or stone coal may be used and 3 is an
opening or draft-flue to cause a speedy and continuous combustion.
The cleaner-5 is for the purpose of clearing the grate so as to
lack of the upper part of the receiver- No. 1 a pipe projects with an elbow
leading up to and communicating with the horizontal connected pipe B
into which the smoke is discharged passing from one to the other until its
heat is exhausted; thence returning to the receiver by an additional pipe
is discharged into the chimney.

It is to be observed that the receiver- No. 1 is a double wall of brick within
which the apparatus is erected or placed the outer one being 10 inches
the inner one 2 $\frac{1}{2}$ inches thick; with a space between them of 2 inches filled in
with phosphorous charcoal to act as a non conductor to the heat and
cold. Within the receiver- No. 1 there are horizontal pipes equal in
diameter to the apartments which may be desired to be heated. These pipes
are heated as will from the fire of the grate as by the hot air confined
within the receiver. 4, 4 are pipes that receive the cold air from the
apartments intended to be heated of which the line 5, 5 is the floor. Through
these pipes the cold air is being drawn from them the hot air descend

to a coil within the body of the pipe 2, passing then through 11 and continuing towards the gate the air forced through remains again by a continuation of the pipe to a level with the lower part of the receiver 1 and by one of the ports of the piston from the open piping to the receiver 1 but then the pipe being further continued by an other upward, the hot air passing through it is conveyed to the pipes No. 6, which lead to and supply the apartments therewith. Then latter pipes 6 are so constructed being a double tube a larger one, having a space between them filled with powdered charcoal, which is not only impervious to the outside air but prevents any heat escaping from them otherwise their utility would be rendered in a great measure abortive. 77 are valves to admit the atmosphere or cold air from without, or rather the circulating air of the apartment, before the apparatus is constructed, which piping into the chamber C, puts in propelling the rarefied air that has been generated into the pipe to the conducting pipes 6. Thus as pipe 6 discharges its rarefied or hot air into the apartment it being lighter than the cold air rises above and forces the cold air into the pipe 4. After the demand being satisfied and this again吸出 as before noted it is discharged into the conducting pipe 6. 8 is a nozzle of a capacity suited to the size & dimensions of the apparatus which is kept full with water within the chamber C by means of a pump 9 and is introduced by the steam or vapor produced from it which rising and mixing with the rarefied air passes into it through the pipe 6 into the apartment thereby propelling the great a rarefaction of the hot air and reduces it as near as possible to the elasticity of atmosphere air.

The whole apparatus may be put up in the cellar or basement story of a house, from which the hot or cold air pipes may be carried over extended to every apartment whether in the first, second or third floors, piping within the walls or otherwise it by casting, should an apartment become hot, much heat will come to precipitately remove by closing the valve at the upper end of the pipe 6. The construction here claimed and classified to be.

553

Secured by Seller's Patent consists in the combination arrangement
and application of the several parts of the before-described apparatus for
heating rooms, particularly the double-walled chamber containing
the furnace. Charcoal which furnishes the apparatus and forced as
a conductor for Warm or Cold air. It receives with the pipes connec-
ted with it the continuous pipes that receive the cold air from the
apparatus to be heated, the double pipes with 'pumice & charcoal' and
the reservoir for containing water for tempering the heated air. And it
is here declared that the subscriber does not ^{confer} ~~confer~~ to the particular
dimensions of the parts and number of pipes used, as herein set forth
but intends to vary them according to circumstances and the situation in
which the apparatus is to be erected.)
